JET PROPULSION DEVICE FOR OPERATION THROUGH FLUID MEDIUM AND METHOD OF OPERATING IT

Fritz Zwicky, Pasadena, Calif., assignor, by mesne assignments, to Aerojet-General Corporation, Cincinnati, Ohio, a corporation of Ohio

Application April 28, 1945, Serial No. 590,833

18 Claims. (Cl. 60—35.6)

This invention relates to propulsion devices of the type adapted to propel crafts, planes or the like through a fluid medium, and more particularly to jet propulsion means and methods.

The principal object of this invention is to improve the operating performance and efficiency of such devices.

In my copending application, Serial No. 558,219, filed October 11, 1944, I have disclosed and claimed a jet propelled device, adapted to be driven through an air medium in the form of an elongated duct or channel having an entrance at the front through which the fluid from the medium may enter and an exhaust nozzle at the rear through which it may exit. In the operation of that device, fuel is burned within the duct, and the heat of combustion thereby generated is transmitted to the mass of air entering the duct. The air and combustion products are forced through the exhaust nozzle at a high velocity and the reaction thereby created produces the propulsive force.

In the apparatus described in my said copending application the gases and heat are formed by the combustion of a fuel-air mixture which is fired in the combustion chamber at either atmospheric pressure or the pressure built up in the system above atmospheric, by its structural design.

In accordance with my present invention I obtain improved efficiency from a jet propelled duct operating in an air medium by compressing the fuel mixture each time just before it is fired. The firing of the mixture in this manner converts a greater proportion of the available thermal energy from the fuel into useful work than would otherwise be obtained from exploding the same amount of fuel without compression.

I provide the desired precompression of the regular or main fuel charge by exploding somewhere in the region of the main fuel mixture a preliminary charge which precedes the main explosion of the regular fuel mixture thereby placing it under pressure. The effect is advantageously procured by exploding such a preliminary charge in a chamber within which the regular charge is to be burned. The preliminary charge can be one which burns at a lower temperature or pressure, or both, than the regular charge; and the increased temperature or pressure, or both, caused by the explosion of the preliminary charge may be employed to ignite the regular charge.

A preferred feature of my invention is the firing of a preliminary explosive charge in such a manner that the main explosive charge is subjected to pressure from both ends of the main firing chamber. The compressive preliminary explosion may also be created, for example, by the use of substances which spontaneously explode when contacted with air, or, which may be catalytically exploded in air. The compressed charge may also be fired by some suitable means such as a spark plug or hot spot if necessary. This type of an explosion in which each explosion of a main charge is preceded by a preliminary explosion is hereafter referred to as a "cascading explosion."

2

Another feature of my invention is the provision of a specially designed cascading explosion firing chamber within the duct. This is designed to admit into a central tube located within the firing chamber a substance or explosive mixture which is more easily ignited or oxidized than the main fuel charge.

The foregoing and other features of my invention will be better understood by the detailed description and the accompanying drawings in which:

10 Fig. 1 is a longitudinal cross section view showing the device in which this invention is employed;

Fig. 2 is a cross section view taken on the line 2—2 of Fig. 1 showing the fuel injectors and firing plugs used in an apparatus employing this invention;

15 Fig. 3 is an enlarged cross section view of the firing chamber and central firing tube shown in Fig. 1;

Fig. 4 is a broken detail view of the front elevation of the valve assembly in the valve housing;

Fig. 5 is a perspective view of one of the blades;

20 Fig. 6 is a perspective view partly in cross section showing the valve blades interleaved between two valve members;

Fig. 7 is a perspective view looking up from beneath one of the channel members;

25 Fig. 8 is a perspective view showing one of the channel blades for use in two channels simultaneously;

Fig. 9 is a broken view in cross section showing an alternative cascading firing chamber equipped to handle substances spontaneously decomposable in air;

30 Fig. 10 is a broken view in cross section showing an alternative form of cascading firing chamber adapted to handle catalytically decomposed substances;

Fig. 11 is a broken view in cross section showing an alternative form of cascading firing chamber;

35 Fig. 12 is a cross section view taken on line 12—12 of Fig. 11, showing the nozzle plate;

Fig. 12a shows a detail taken in cross-section at line 12a—12a of Fig. 12.

Fig. 13 is a broken view partly in cross section showing 40 another embodiment of a cascading firing chamber; and

Fig. 14 is a graph showing the effect of cascading compared to the single explosion operation.

The device illustrated in Figs. 1 to 3 comprises a shell 1 forming a duct or passageway through which air is

45 adapted to flow, the air entering at the mouth 7 and leaving at the exhaust nozzle 12. The shell 1 comprises a leading section 2 which is preferably circular for about one-third of its length from the entrance 7 and then undergoes a transition to correspond to the rectangular outline

50 of center section 3. A square spacer frame 17 fits between sections 2 and 3. The rectangular portion of center section 3 tapers slightly from the front to a point beyond the center of the section where it begins a transition from rectangular to circular in such a manner that it will corre-

55 spond to the front end of circular tail section 4. Tail section 4 continues to taper toward the rear up to a point about two-thirds its length and at this point it enlarges slightly again as it approaches the nozzle opening 12. Sections 2, 3 and 4 are bolted together by a series of bolts

60 5 and 6. Tail section 4 is provided with a series of radiation fins 8 to insure cooling of the unit.

A valve assembly 36, for controlling the flow of the fluid through the duct, is located near the forward end of the channel and divides the duct into a forward portion

65 and a rear portion. The construction of blade valve assembly 36 is described in detail with reference to Figs. 4, 5, 6 and 7. This valve is built up of an assembly of alternating flexible blades 72 and rigid channel members

71. Each rigid channel member 71 comprises a rectangular-shaped plate 74 the upper face of which is provided with a curvature as shown in Figs. 6 and 7. The

lower surface of plate 74 is provided with a number of channels 77 formed by channel members 80 which are integral with the plate and run parallel with each other as shown. These channel partitions 80 taper in depth being deeper at the leading edge 79 and tapering at the rear edge 83 to coincide with the thickness of the rear edge of the blade. The upper surface of members 71 is provided with a series of parallel ridges 84 corresponding with a number of channels and are positioned so as to be centered with reference to each respective channel.

In assembling the valve assembly 36 several flexible blades 72 are alternately interleaved between several channel members 71 and are firmly held near their leading edge 73 between the channel strips 80 of one channel member and the front flat face 82 of the next. These valves and rigid channel members are further held together by a series of bolts 85 which pass through the holes 75 and 75a drilled in the blades and channel members. When a series of these valves and channel members are installed to form the completed valve assembly 36 they completely occupy the rectangular space in the region preceding the firing chamber 40. For purpose of assembly these valves slide into a machined rectangular area 10 cut in the front end of firing chamber insert section 9 and are held in place at the rear by shoulder 16 and in front by spacer 17. The arrangement of these valves in the valve receiver is shown in Figs. 1, 4, 9, 10, 11 and 13.

Fig. 6 shows a perspective view illustrating one of the flexible blades 72 sandwiched between two adjacent channel members 71.

Fig. 7 is a view from the underneath side of channel member 71 and shows a portion of the blade valve including blade 72. The curvature of the face 74 of each channel member is such that the rear edge 83 of each channel comes down to meet the rear edge 78 of the corresponding adjacent valve blades 72 as more clearly shown in Fig. 6. The arrangement is such that the lower edge 81 of all the channel partitions 80 of each channel member is flat against the flat surface of blade 72 as illustrated in Fig. 7. By this assembly arrangement the rear edges 78 of the flexible blades 72 are enabled to vibrate so as to alternately contact and move away from the rear edges of 83 of members 71. This creates the valve action as the valve is closed when blades 72 are tight against the channel members of valve body 71.

There is located within shell 1 a combustion chamber 40 which is held in place by vanes 31 which are attached to insert section 9 and to firing chamber 40 by any suitable means such as welding. Insert section 9 is rectangularly shaped and slides into the recessed section 39 cut in the center section 3. The insert 9 is clamped into position against shoulder 18 when section 2 and spacer 17 are bolted to section 3. The firing chamber 40 is cylindrical in shape and is provided with fuel injectors 43. Injector 43 is preferably a spray nozzle type of injector capable of introducing the fuel as a fine spray or mist.

A cylindrical tube 20 of smaller diameter than the main firing chamber 40 is held in position within firing chamber 40 by a series of supporting legs 21 fastened to the small tube and the firing chamber 40 by any suitable means such as welding. The leading end 22 of the tube 20 is slightly flared making the tube slightly larger in diameter at this point than throughout the rest of its length. Tube 20 is equipped with a fuel injector 23 located near the forward or flared end 22 of the tube. A sparking device 24 is provided in the tube. Tube 20 is shorter in length than the main firing chamber 40. This is done to provide a region at either end of small tube 20 where the effects of the explosion within the tube can act upon the main explosive charge in firing chamber 40.

Fuel under pressure, for example, gasoline, is introduced into the main firing chamber 40 through conduits 25 which feed injectors 43. A more reactive or explosive

material is fired in the smaller tube. It is introduced into that region through conduits 26 and injector 23.

The way in which the apparatus operates is as follows: Tube 20 is charged with a more easily explodable fuel than firing chamber 40. For example, if the fuel supplied to chamber 40 is gasoline, the fuel supplied to tube 20 may be oxygen and hydrogen, propane, butane, pentane, or other light hydrocarbons. The more stable fuel is supplied to firing chamber 40 simultaneously with the fuel supplied to the smaller firing tube 20. The charge in tube 20 is detonated and the force of the explosion creates regions of pressure at both ends of the firing chamber 40. This operation places the charge in 40 under pressure. When this charge has been compressed a sufficient degree and the temperature has been raised to the proper point the charge in chamber 40 will automatically explode. The force of the explosion will cause valve 36 to shut off the flow of air entering through mouth 7 and will permit products of combustion to escape out of both ends of firing chamber 40. Part of the products of combustion pass directly toward the rear and the remainder issue from the front of firing chamber 40 and then escape toward the rear through the outer duct 38. As soon as the pressure generated by the explosion diminishes to the point where it is exceeded by the pressure acting on the forward side of the valve 36 the valve will again open and permit free flow of air throughout the entire duct. As soon as the valve opens to permit scavenging of the products of the prior explosion of a new charge of fuel is admitted into the combustion chamber which when mixed with the air forms a new explosive charge. Likewise, a new charge of the more easily explodable mixture is introduced into the smaller firing chamber within the large firing chamber 40. The smaller charge is exploded and the entire process of combustion repeated. The operation consists of a series of these double explosions rapidly following each other in such a manner that a substantially continuous thrust is produced.

Considering for a moment one of these double or cascaded explosions, the effect of the preliminary explosion in the tube 20 upon the power to be derived from the ultimate explosion in chamber 40 is clearly illustrated in the graph shown in Fig. 14 in which the pressure developed by the cascading of the explosions is shown compared to the effect of a single explosion. The graph shows a plot of time against pressure. The pressure reached at the end of the initial detonation is shown by P_i and the resulting pressure developed after the explosion of the second, or more difficultly ignitable material in tube 40 is indicated at point P_c . The graph taken during the operation of the device shows clearly the gain in pressure and work which are made available when my invention is employed.

A modification of the arrangement of Fig. 1 which may be used for producing a similar result is illustrated in Fig. 9. The apparatus partly shown in Fig. 9 is similar to that in Fig. 1 except that the firing chamber insert 9 of Fig. 1 is replaced by a firing chamber section insert 19.

This section possesses similar features to the one shown in Fig. 1 with the exception that the valve adjoins the firing chamber.

In apparatuses of the type employing the firing chamber adjoining the valve as shown in Figs. 9, 10, 11, and 13 all valve blades which come in contact with the circular area of firing chamber are cut as shown in Fig. 8 by suitable slots 76 to permit various portions of the valve blade to act independently. The distance between these slots will vary according to the portion of the firing chamber area intersected by the blades in such a manner that the blades near the top and the bottom will have slots 76 close together, while those which pass through the center of firing chamber area will be slotted a maximum distance apart. It can readily be seen that this arrangement permits the valve blade section adjoining

the firing chamber to operate independently of that portion of the same blade which opens into the duct 38. Provision is also made for the introduction of substances which are spontaneously ignitable when coming in contact with air at ambient or elevated chamber temperatures. Spray injectors 61 introduce one of these substances into the rear region of the firing chamber 40 after the forward region of the chamber has been filled to the desired extent with the combustible mixture by injectors 43. When the substance entering through injectors 61 comes in contact with sufficient air it explodes and this explosion compresses the charge in the forward portion of the chamber. The forward charge may then either be ignited by spark plug 41 or may be exploded automatically when the pressure and temperature are elevated to the proper degree. Substances which are suitable for spontaneous decomposition in air are aluminum borohydrides, boron hydrides such as B_2H_6 , trimethylborine, aluminum trimethyl and zinc diethyl.

Another alternative which may be substituted for the firing chamber assembly of Fig. 1 is shown in Fig. 10 and a substance which is catalytically decomposable in air is employed in place of a substance which is automatically decomposable in air. A catalyst bed 62 is provided at some convenient position such as the nose portion of a deflector 46 to support the catalytic bed 62. This catalytic bed performs the function of initiating the decomposition of the substance. Propellant substances of this class are, for example, nitromethane and nitroparaffin. The catalyst may be platinum sheet or manganese dioxide mixed with other suitable metal oxides to increase its strength. Conduits 60 are installed in the rear of the firing chamber and through nozzles 60a spray catalytically decomposable substances against the bed. This assembly is otherwise similar to the first alternative shown in Fig. 9. Spark plugs 41 may be provided in the forward portion of the firing chamber of Fig. 10 to make certain that the decomposition or ignition of the heavier fuel-air mixture takes place.

Another embodiment of my invention is shown in Fig. 11. This apparatus may be substituted for firing chamber insert 9 used in Fig. 1. This firing chamber insert 19b comprises forward firing chamber 100 adjacent to valve bank 36 and a rear firing chamber 101. Chambers 100 and 101 are held in a central position by vanes 31. Firing chambers 100 and 101 are separated by a nozzle plate 102 shown in Figs. 11 and 12. Nozzle plate 102 is secured in the proper position to the walls of the firing chamber by any suitable means such as welding. Nozzle plate 102 is equipped with a plurality of small nozzles 106, preferably of the De Laval type. One of the nozzles is shown in cross-section in Fig. 12a. These nozzles 106 are arranged in such a manner that the axis of each nozzle is parallel to the longitudinal axis of the firing chamber and perpendicular to the cross sectional area of the plate. The nozzles are preferably uniformly distributed over the plate area so as to insure equal conduction between the firing chambers 100 and 101. The opening 107 at the forward end of nozzle 106 is larger in diameter than the discharge end 108. A fuel mixture such as hydrogen and oxygen, or pentane and air, which is more readily ignited than the main fuel used in the propulsion of the apparatus, is introduced into chamber 101 through injector nozzle 104. At the same time the main fuel-air charge is introduced into firing chamber 100 through injector 103. The mixture in chamber 101 is flashed by any suitable means such as a spark plug 105. The pressure and the heat generated by the explosion in chamber 101 acts upon the less readily ignitable fuel-air mixture in chamber 100 and places the mixture under pressure, and the heat generated by the explosion in chamber 101 also is partly transmitted into the chamber 100. When this pressure and temperature are sufficiently high to ignite the mixture in chamber 100, the fuel-air mixture in the forward chamber will explode driving the

products of combustion and the heat toward the rear through the nozzle plate 102 and into the incoming mass of air which is entering through duct 38 which surrounds firing chamber 100 and 101. With some types of fuels it may be necessary to use suitable ignition means such as a spark plug 109 or a hot spot located in the forward end of the firing chamber 100. The air passing over the firing chamber through the duct 38 is warmed by the radiation of heat given off by the firing chamber after each explosion has occurred. In this manner the air which is mixed with the products of combustion has already gained additional energy and velocity.

Another form of apparatus which is suitable to carry out my invention is illustrated in Fig. 13. In this apparatus the firing chamber insert 19c replaces insert 9 holding the firing chamber of Fig. 1. This insert section comprises a central firing chamber 110 held in position by vanes 117. Firing chamber 110 is provided with three sets of injectors 111, 112, and 113 which have firing plugs 114, 115 and 116 located rearwardly of each set of injectors.

Fuels which are readily ignitable by spark plugs or hot spots are introduced into the firing chamber by nozzles 111 and 113 and at the same time a fuel which requires more pressure and heat to cause its spontaneous decomposition is introduced through nozzle 112. Spark plugs 114 and 116 fire the charge which has been introduced through injector 111 and 113. The pressure waves created by the explosion of the easily ignitable substance at either end of the firing chamber travel toward the center in such a way as to compress and heat the less easily ignitable fuel which is injected between them. Again this fuel under pressure may be set off by any suitable means such as spark plug 115 or may be ignited when the temperature and pressure developed by the simultaneous explosion at each end of the firing chamber have raised the pressure and temperature of the main charge to a sufficient degree to cause its spontaneous ignition. A similar procedure may be used with a single fuel. This may be injected through forward injector 111 and allowed to travel the length of the firing chamber. When the chamber is filled the charge is flashed at both ends by plugs 114 and 116 thereby compressing the central portion of the fuel before it is fired.

I claim:

1. A reaction propelled device adapted for propulsion through air comprising a duct having an inlet opening and an exhaust nozzle, a valve separating the duct into a forward and rear portion, a combustion chamber located within the rear portion, an auxiliary combustion chamber of shorter length than the first-mentioned combustion chamber located within the first-mentioned combustion chamber, means for supplying a combustible charge to the first-mentioned combustion chamber and means for supplying an explosive charge in the auxiliary combustion chamber, and means for initiating the explosion of the explosive charge in the auxiliary combustion chamber.

2. A reaction propelled device adapted for propulsion through air comprising a duct having an inlet opening and an exhaust nozzle, a valve separating the duct into a forward portion and a rear portion, said valve being operable to admit air from the forward portion to the rear portion when the pressure in the forward portion exceeds that in the rear portion and to prevent any flow of gas from the rear portion to the forward portion when the pressure is greater in the rear portion than in the forward portion, a main combustion chamber located within said rear portion, an auxiliary combustion chamber of shorter length than the main combustion chamber located within the main combustion chamber, means for supplying a combustible charge to the main combustion chamber and means for supplying an explosive charge in the auxiliary combustion chamber, and means for initiating

ing the explosion of the explosive charge in the auxiliary combustion chamber.

3. A reaction propelled device adapted for propulsion through air comprising a duct having an inlet opening and an exhaust nozzle, a valve separating the duct into a forward portion and a rear portion, said valve being operable to admit air from the forward portion to the rear portion when the pressure in the forward portion exceeds that in the rear portion and to prevent any flow of gas from the rear portion to the forward portion when the pressure is greater in the rear portion than in the forward portion, a combustion chamber in the rear portion, said combustion chamber being contiguous with said valve and of smaller cross-section area than the inside cross-section area of the part of the duct within which it is located, means for introducing a combustible charge in a region of said combustion chamber, means for introducing a second combustible charge more readily combustible than the first-mentioned charge in another region of said combustion chamber, and means for initiating the combustion of the second combustible charge, thereby producing combustion of the first-mentioned charge.

4. A reaction propelled device adapted for propulsion through air comprising a duct having an inlet opening and an exhaust nozzle, a valve separating the duct into a forward and rear portion, said valve being operable to admit air from the forward portion to the rear portion when the pressure in the forward portion exceeds that in the rear portion and to prevent any flow of gas from the rear portion to the forward portion when the pressure is greater in the rear portion than in the forward portion, a combustion chamber in the rear portion, said combustion chamber having an opening which is contiguous with said valve and another opening away from said valve, and being equipped with means for introducing a main combustible charge in the central region of the chamber and means at either side of said combustion region for introducing an explosive charge that may be more easily ignited than the main combustible charge, and means for initiating said charges at either side of said central region.

5. A reaction propelled device adapted for propulsion through air comprising a duct having an inlet opening and an exhaust nozzle, a valve separating the duct into a forward and rear portion, said valve being operable to admit air from the forward portion to the rear portion when the pressure in the forward portion exceeds that in the rear portion and to prevent any flow of gas from the rear portion to the forward portion when the pressure is greater in the rear portion than in the forward portion, a combustion chamber in the rear portion, said combustion chamber having an opening which is contiguous with said valve and another opening away from the valve, means in said combustion chamber for introducing a combustible charge in a region of the said combustion chamber near the valve and means for introducing a self-explosive substance capable of spontaneous ignition in air at a region of the combustion chamber away from the valve.

6. A reaction propelled device adapted for propulsion through air comprising a duct having an inlet opening and an exhaust nozzle, a valve separating the duct into a forward and rear portion, a combustion chamber in the rear portion, said combustion chamber having an opening which is contiguous with said valve and an opening away from the valve, means for introducing an explosive charge in a forward region of the combustion chamber, means for introducing a substance which is catalytically decomposed in air in a rear region of the chamber, catalytic means for initiating the decomposition of the air explodable substances, said means located in the region where the catalytic explodable substance is introduced.

7. A reaction propelled device adapted for propulsion through air comprising a duct having an inlet opening and an exhaust nozzle, a valve separating the duct into a forward and rear portion, said valve being operable to admit air from the forward portion to the rear portion

when the pressure in the forward portion exceeds that in the rear portion and to prevent any flow of gas from the rear portion to the forward portion when the pressure is greater in the rear portion than in the forward portion, a main tubular combustion chamber open at both ends and located downstream from said valve and of smaller diameter than the duct thereby creating a channel within the duct and surrounding the main combustion chamber, a second tubular combustion chamber open at both ends and of shorter length than the main tubular chamber and located within the main combustion chamber, means for supplying a combustible charge to the main tubular combustion chamber, means for supplying an explosive charge into the second tubular combustion chamber, and means for initiating the explosion within the second combustion chamber.

8. A reaction propelled device adapted for propulsion through air comprising a duct having an inlet opening and an exhaust nozzle, a valve separating the duct into a forward and rear portion, said valve being operable to admit air from the forward portion to the rear portion when the pressure in the forward portion exceeds that in the rear portion and to prevent any flow of gas from the rear portion to the forward portion when the pressure is greater in the rear portion than in the forward portion, a main tubular combustion chamber open at both ends and located downstream from said valve, an inner tubular combustion chamber open at both ends and of shorter length than the main tubular chamber located within the main combustion chamber, means for supplying a combustible charge to the main tubular combustion chamber, means for supplying an explosive charge into the inner tubular combustion chamber, ignition means to ignite the explosive charge in the inner tubular combustion chamber, and ignition means provided in the main tubular combustion chamber to assist the decomposition of the main combustible charge.

9. A reaction propelled device adapted for propulsion through air comprising a duct having an inlet opening and an exhaust nozzle, a valve separating the duct into a forward and rear portion, said valve being operable to admit air from the forward portion to the rear portion when the pressure in the forward portion exceeds that in the rear portion and to prevent any flow of gas from the rear portion to the forward portion when the pressure is greater in the rear portion than in the forward portion, a tubular combustion chamber located downstream from said valve and of smaller diameter than the inner diameter of the duct thereby providing a space for air to pass by the combustion chamber, said combustion chamber having an inner combustion chamber of shorter length than the main combustion chamber, means for supplying a combustible charge to the main combustion chamber, means for supplying an explosive charge to the inner combustion chamber, and means for initiating the explosion in said inner combustion chamber.

10. A method of operating a combustion motor having a combustion chamber, which comprises introducing a combustible charge into the combustion chamber and introducing a more easily decomposable explosive charge on either side of the main combustible charge, exploding the more readily combustible charges and promoting the explosion of the main combustible charge by employing pressure and temperature created by the explosion of the more easily decomposable charges.

11. The method of operating an internal combustion motor having a main combustion chamber enveloping a smaller combustion chamber which opens into the main chamber, which comprises introducing a combustible charge in the main combustion chamber and introducing an explosive charge in the smaller combustion chamber, igniting the charge in said smaller combustion chamber thereby creating pressure at the opening of the smaller combustion chamber and exploding the main combustible

charge by employing the pressure and temperature generated by the preliminary explosion.

12. The method of operating a reaction propelled device having a main combustion chamber with front and rear openings and surrounded by an air duct, said chamber enveloping a smaller combustion chamber of shorter length than the main combustion chamber, comprising introducing a combustible charge in the main combustion chamber, introducing an explosive charge into the smaller combustion chamber, igniting the charge in said smaller combustion chamber and exploding the main combustible charge in the main combustion chamber by the pressure and temperature created by the explosion of the charge within the smaller combustion chamber, said explosion discharging the gases from the rear and front openings of said main combustion chamber in such a manner that the air in the region between the combustion chamber and the duct is heated and is forced toward the rear of the duct at increased velocity and temperature.

13. A reaction propelled device adapted for propulsion through air comprising a duct having an inlet opening and an exhaust nozzle, a valve dividing the duct into a forward portion and a rear portion, a tubular combustion chamber located within the rear portion, the longitudinal axis of the tubular chamber being colinear with the axis of the duct, means for introducing a combustible charge in a region of said tubular combustion chamber, means for introducing a second charge more combustible than the first-mentioned charge, in another region of the chamber, and means for initiating the combustion of the second combustible charge, whereby the combustion of the second charge ignites the first-mentioned charge, thereby creating gases which are expelled through the exhaust nozzle.

14. A reaction propelled device adapted for propulsion through air comprising a duct having an inlet opening and an exhaust nozzle, a valve dividing the duct into a forward portion and a rear portion, whereby air is adapted to enter the inlet opening, and pass through the valve when the valve is open, and flow out the exhaust nozzle, a combustion chamber located within the rear portion with a space between the combustion chamber and the inner wall of the duct so that the air can readily flow past and around the combustion chamber, means for introducing a combustible charge in a region of said combustion chamber, means for introducing a second combustible charge more combustible than the first-mentioned charge, in another region of the chamber, and means for initiating the combustion of the second combustible charge, whereby combustion of the second charge ignites the first-mentioned charge, thereby creating gases which are expelled with the air through the exhaust nozzle.

15. A device according to claim 14 in which the combustion chamber has openings at both ends thereof, one opening being located to face the valve and the other opening being located to face the exhaust nozzle.

16. A reaction propelled device adapted for propulsion through air comprising a duct having an inlet opening and an exhaust nozzle, a valve dividing the duct into a forward portion and a rear portion, a tubular combustion chamber located within the rear portion, the longitudinal axis of the tubular chamber being colinear with the axis of the duct, an auxiliary tubular chamber, the combustion chamber and the axis of the auxiliary chamber being colinear with the axis of the combustion chamber, means

65

for introducing a combustible charge into the combustion chamber and means for introducing a second charge more combustible than the first-mentioned charge in the auxiliary chamber and means for initiating the combustion of the second combustible charge, whereby the combustion of the second charge in the auxiliary chamber ignites the first-mentioned charge in the combustion chamber thereby creating gases under pressure which cause the gases to be expelled through the exhaust nozzle.

17. A reaction propelled device adapted for propulsion through air, comprising a duct having an inlet opening and an exhaust nozzle, a valve dividing the duct into a forward portion and a rear portion, the valve being constructed to open when the pressure in the forward portion is greater than in the rear portion and to close when the pressure in the rear portion is greater than in the forward portion, a combustion chamber situated in the rear portion, and an auxiliary combustion chamber situated within the main combustion chamber, means for introducing a combustible charge in the main combustion chamber and means for introducing a second combustible charge more combustible than the first-mentioned charge in the auxiliary chamber, means for initiating the combustion of the second combustible charge whereby the combustion of the second charge ignites the first-mentioned charge in the main combustion chamber, thereby creating gases under pressure which close the valve causing the gases to be expelled through the exhaust nozzle.

18. A reaction propelled device adapted for propulsion through air, comprising a duct having an inlet opening and an exhaust nozzle, a valve dividing the duct into a forward portion and a rear portion and being constructed so that when the pressure is greater in the forward portion than in the rear portion the valve is opened, and when the pressure is greater in the rear portion than in the forward portion, the valve closes, a tubular combustion chamber open at both ends and located within the rear portion so that it is coaxial with the longitudinal axis of the duct, one of the openings being placed adjacent the valve, and the other opening being directed toward the exhaust nozzle, injection means for injecting a main combustible charge into the combustion chamber at a position near the valve, a second injection means for injecting a second combustible charge more readily combustible than the first-mentioned charge at a position within the combustion chamber, more remote from the valve than the first-mentioned injection means, means whereby ignition of the more readily combustible charge serves to ignite the main combustible charge thereby producing gases under pressure which operate to close the valve causing the gases to be exhausted through the exhaust nozzle.
